TETHERED BALL GAME

William Edward Bonang, 139 Sydney St., Saint John,
New Brunswick, Canada
Filed Jan. 30, 1961, Ser. No. 85,794
4 Claims. (Cl. 273—98)

The invention relates to a ball game toy.

Many games and toys are played with balls. In many such games a resilient rubber ball is elastically connected directly to a rigid wooden handle.

By the present invention there is provided a ball game toy comprising a ball, a handle attached to said ball, a further ball, and means for elastically connecting said further ball to said first ball.

In practice, both hereinbefore mentioned balls are made of resilient rubbery material, such as sponge rubber. Also, in practice, the further ball is smaller than the first ball, and the large ball is used as the striker element.

In the drawings which illustrate embodiments of the invention—

FIG. 1 is an elevation, partly in section, of one embodiment of the invention.

FIGS. 2-7 are elevation views of other embodiments of the invention, and

FIG. 8 is a view showing the operation of the present invention.

As seen in FIG. 1, the present invention includes a striker 10 and a ball 11 adapted to be stricken.

The striker 10 comprises a resilient ball 12, usually of sponge rubber to which is attached a hand grip 13. The hand grip is attached by means of a wire handle 14 which fits into diametrically opposed holes 15 in the sponge rubber ball 12. The handle may be of one piece of wire passing completely through the hand grip (as shown) or it may consist of two separate pieces of wires passing through the extremities of the hand grip.

The ball adapted to be stricken is shown at 16 and it, too, is preferably formed of sponge rubber. It is provided with a hole bored therethrough, through which an elastic rubber strip 18 is adapted to pass. The elastic rubber strip 18 is prevented from re-emerging from the hole 18 by means of knot 20. The other end of the elastic rubber strip 18 is attached to the striker, by means of knot 21 onto handle 14.

This provides a ball game toy comprising a striker (which is formed of a sponge rubber ball and a handle) and a sponge rubber ball adapted to be stricken, and means resiliently connecting the striker to the ball.

The embodiment shown in FIG. 2 differs from that shown in FIG. 1 only in the manner in which the elastic rubber strip is attached to the striker. As shown, the elastic rubber strip 18 passes through a hole 19 drilled through the sponge rubber ball 12, and is prevented from re-emerging by means of knot 24.

The embodiment shown in FIG. 3 differs from that shown in FIG. 1 only in the manner in which the elastic rubber strip is attached to the ball being stricken. As shown, the elastic rubber strip 18 is attached to the sponge rubber ball 16 by means of staple 22.

The embodiment shown in FIG. 4 is a modification of the embodiment shown in FIG. 3, wherein the elastic rubber strip is attached to the striker in a different manner. As shown, the elastic rubber strip 18 is attached to the sponge rubber ball 16 by staple 22 and to the sponge rubber ball 12 by staple 23.

The embodiments shown in FIGS. 5 and 6 illustrate a different manner of forming the striker. As shown in

2

FIG. 5, the striker is formed by attaching a hand grip 13 directly to the sponge rubber ball 12 by means of connector 25. The elastic rubber strip is then connected to the sponge rubber ball 12 by means of staple 23.

5 The embodiment shown in FIG. 6 differs from that shown in FIG. 5 in respect of the manner of resiliently connecting the ball adapted to be stricken to the striker. As shown, the elastic rubber strip 18 is connected to the sponge rubber ball 12 by staple 23, and to the sponge

10 rubber ball 16 by the staple 22.

The embodiment shown in FIG. 7 represents still another form of embodiment concerning which many variants are possible. But the embodiment as shown has the elastic rubber strip 18 pass through hole 17 in sponge 15 rubber ball 16 and retained in position by knot 20, and it also has the elastic rubber strip pass through the hole 19 in sponge rubber ball 12 and retained in position by knot 24. The handle, instead of being diametrically opposite to the part of the sponge rubber ball 12 which is 20 adapted to be contacted by the sponge rubber ball 16, now is situated at right angles to the hole 19 passing through sponge rubber ball 12.

Numerous other variants of this invention are, of course, possible.

25 In FIG. 8 is seen one practical embodiment of this invention, the striker comprises a hand grip 13 and a handle attached to a large sponge rubber ball on which is preferably shown an illustration of a baseball player. The ball adapted to be stricken is a small sponge rubber 30 ball 16 having indicia thereon indicative of a baseball.

I claim:

1. A ball game toy comprising a striker, said striker including a resilient ball and an inelastic hand grip directly attached thereto, a further resilient ball, and resilient 35 and elastic means for attaching said further ball to said striker.

2. A ball game toy comprising a striker, said striker including a sponge rubber ball and an inelastic hand grip directly attached thereto, a further sponge rubber ball, 40 and an elastic rubber strip for attaching said further ball to said striker.

3. A ball game toy comprising a striker, said striker including a sponge rubber ball, a rigid inelastic hollow cylindrical hand grip and a handle passing through said 45 hollow hand grip, directly attaching said hand grip to said ball, a further sponge rubber ball smaller than the aforesaid sponge rubber ball and an elastic rubber band fixed to said further sponge rubber ball and fixed to said handle, thereby resiliently and elastically connecting said 50 further sponge rubber ball to said striker.

4. A ball game toy comprising a striker, said striker including a sponge rubber ball, a rigid inelastic hollow cylindrical hand grip, and a handle passing through said hollow hand grip, directly attaching said hand grip to 55 said ball, a further sponge rubber ball smaller than the first mentioned sponge rubber ball, and an elastic rubber band passing through a hole in said further sponge rubber ball and fixed to said handle, thereby resiliently and elastically connecting said further sponge rubber ball to said 60 striker.
